MACHINE FOR BINDING BOOKS

Harley C. Alger and Philip A. Frazier, Chicago,
Ill., assignors, to R. R. Donnelley & Sons Company,
Chicago, Ill., a corporation of Illinois

Application May 9, 1931. Serial No. 536,116

6 Claims. (Cl. 91—55)

This invention relates particularly to an improved machine for gluing books whereby a firmer bond is obtained between the glue and the pages of the books, and is adapted to be used with a bookbinding and covering machine of the type shown in the patent to Bredenberg No. 1,248,252, granted November 27, 1917.

Heretofore, in applying glue to the freshly cut back of the book, great care has been exercised to have the glue of the proper consistency and at the right temperature to insure a proper union between the glue and the back of the book, and later in the operation, between the glue and the cover. It is difficult in practice to get a glue of a consistency to perform properly both of these functions. A glue of the right consistency to enter the spaces between the edges of the sheets is much too thin to hold the cover. If it is of a proper consistency to hold the cover, it is much too heavy to afford a firm bond between the leaves of the book.

An object of this invention is to overcome this difficulty and to provide a machine for applying glue which will be of the proper consistency for both operations.

This and other objects, as will hereinafter appear, are accomplished by this invention which is fully described in the following specification, and shown in the accompanying drawings, in which—

Figure 1 is a top plan view of a machine embodying the invention;

Fig. 2 is a partial enlarged side elevation of the same;

Figs. 3, 4 and 5 are partial enlarged sections on the lines 3, 4 and 5 respectively of Fig. 1;

Fig. 6 is a partial enlarged perspective of the trough as viewed on the line 6 of Fig. 5; and

Fig. 7 is a partial enlarged section on the line 40 7 of Fig. 1.

This is a continuation-in-part of our application for Letters Patent, Serial No. 321,818, filed November 26, 1928, which matured into Patent 1,804,392. The present invention is shown as applied to the machine of the patent to Bredenberg No. 1,248,252. For the sake of clearness and to save unnecessary repetition, those parts of the patented machine which are not altered are shown sketchily or are omitted altogether.

The machine comprises a frame having upper and lower tracks or guides 10 (Figs. 1, 7) supported on suitable legs as 11, 12 carried on a base 13. Between the upper and lower guides 10 run the links 14 of a continuous chain which serves to carry the book to be bound through the

machine, and which is propelled by means of a sprocket 15. Broadly, the invention consists in cutting the backs of the books which are previously "gathered" or assembled from a series of signatures. This cutting operation severs and separates all of the sheets so that they are now held in the form of a tablet and require that this cut edge be glued, after which a "super" and cover are applied thereto. The present invention relates, primarily, to an improved machine for performing this gluing operation.

Speaking generally, the book A gripped by the chain while being carried forward is trimmed on the back by means of a suitable cutter, such as the band saw B, after which it passes to the first glue pot C. The trimmed back is given a coat of thin glue which, as will later be described, is worked into the leaves at the back of the book. The book then passes through a chilling device D where the thin glue from the glue pot C will be chilled, and thereby considerably thickened, after which the book is given a second coating of thicker glue as it passes over the glue pot E, after which a super is applied by a mechanism F. The book is then passed on to any form of suitable cover conveyor H where the book is released and the machine is then ready to receive another book to be bound.

The carrier chain of the machine comprises a series of links 14 hingedly connected together by means of pins 16, on the upper and lower ends of which are mounted rollers 17, 18 which pass between the upper and lower channel shaped guides 10. These links 14 are provided with longitudinally spaced and laterally offset openings through which pass guide pins 19 which are attached to opposite ends of clamping plates 20. These plates are normally drawn toward the links 14 by means of springs 21 on the inner ends of the guide pins 19, these springs acting upon a cross bar 22 which is attached at its two ends to the two pins 19. This cross bar carries near its center a roller 23 which is pivotally mounted, and which serves, when pressed outwardly, to force the plate 20 away from the link so as to release the book A held therebetween.

The chain 14 and sprocket 15 travel in a counter-clockwise direction. As the rollers 23 encounter the cam 24 carried by the main frame, the plate 20 is forced outwardly, thereby releasing a book held thereby, and this plate remains in this open position until the roller runs off the opposite end of the cam. The sprocket 15 is mounted upon a shaft 25 which is journaled in

suitable bearings carried by the main frame, and has keyed thereon a bevel gear 26 which is meshed with a driving pinion 27 on a shaft 28. This shaft has a gear 29 meshing with a gear 30 on a shaft 31 which is driven by means of suitable reduction gearing (not shown) from any suitable source of power, such as a motor.

The shaft 28 is provided with a suitable worm and worm wheel, (not shown) which are contained within a gear case 32, and which serve to drive a shaft 33. This shaft drives, through suitable sprockets and a chain 34, a shaft 35 which drives the glue feeding mechanism of the glue pot C. The shaft 35 in turn drives a shaft 36 at the rear end of the glue pot C by means of suitable sprockets and a chain 37 which runs thereover. The shaft 35 has a bevel pinion 38 keyed thereon which meshes with bevel gears 39, 40, these gears being keyed on shafts 41, 42 respectively which are suitably journaled in the glue pot C.

These shafts carry spiral gears 43, 44 which lie immediately beneath the path of the book A to be bound, and dip into the glue of the glue pot and serve to carry this glue up, and to wipe it across the bottom cut back of the book. It will be observed that the direction of travel of these gears is in opposite direction across the bottom of the book, so that these projecting edges are "fanned" or spread first in one direction from normal, and then in the other so as to cause this glue to be thoroughly worked into the back and to both surfaces of the sheets closely adjacent their back edges.

35 This glue is made quite thin and is kept hot by any desired means (not shown) so as to better enable it to penetrate the sheets. Following the gluing gears 43, 44 is a gluing wheel 45 which is carried on a shaft 46 which has a bevel gear 47 meshing with another gear 48, which is carried on a shaft 49 which has a bevel gear 50 meshing with the bevel gear 40. The gluing wheel 45 adds a fresh amount of the thin glue to the bottom of the book and assists further in working the glue in between the sheets.

50 As the book then proceeds it passes through between two oppositely disposed pressing idler rollers 51, 52 (see Fig. 3). These rollers are mounted upon vertical pivots carried by the glue pot C and serve to press the laterally spread edges of the sheets A from the dotted line position to the full line position of Fig. 3, at the same time squeezing out some of the glue which is held between the edges of these sheets. The glue pot C is adjustably carried on standards C'.

55 As the book A passes these rollers it passes over a rotary scraper 53 which is mounted on the shaft 36, this scraper being rotated so that its upper edge runs counter to the edge of the book, thereby scraping from the back of the book any excess glue. The links carrying the books A then pass around the sprocket 15 and as they do so are brought into the semi-circular trough 54 of the chilling mechanism D. The trough 54 has a bottom 55 in which is a series of holes 56 communicating with a passage 57 which extends throughout the length of the trough 54. Near the entering end of the trough 70 is located a container 58 having a removable cap 59 by which it can readily be filled with "dry ice", or the like 60. A current of air is preferably slowly passed over this dry ice by means of a tube 61 from any source of air pressure. When so employed the air passes down

through the cooling medium 60, is chilled to a point well below zero, and passes up through the openings 56 into contact with the glued back of the book A. In this way the glue becomes chilled and considerably thickened by the time 80 it passes out of the opposite end of the mechanism D.

85 As the book leaves the chilling device it passes over the glue pot E filled with a heavy glue which is particularly adapted to hold the 85 cover which is later to be applied. Having chilled the thin glue which has been previously applied, the glued back of the book is now in condition to receive this thicker glue. The glue pot E has a glue feeding roller 62 90 adapted to carry glue to the back of the book, and which is mounted on a shaft 63 which is driven by means of sprockets and a chain 64 from the shaft 33. The shaft 63 also carries a sprocket 65 which drives a sprocket 66, which 95 in turn drives through a gear 67, a gear 68 on a shaft 69. This shaft carries a rotary scraper similar to the scraper 53 which removes the excess glue which has been deposited by the glue wheel 62.

100 Passing the glue pot E the book A next passes over the mechanism F by means of which a super is fed to the glued back of the book. This mechanism is shown in side elevation in Fig. 4, and is operated in timed relation to the 105 positioning of the book A by means of a cam 70 on the shaft 28. This cam serves to operate a lever 71 pivotally mounted at 72. An operating rod 73 is pivotally connected to the opposite end of the lever 71, the upper end of this rod 110 being connected to a sliding block 74 which is normally retracted, as shown in Fig. 4.

115 A roll of open mesh gauze 75 is mounted upon a suitable reel 76 which is carried by the frame 77 of the super mechanism. This gauze passes 115 through between two feed rolls 78, 79, the latter being driven by means of a ratchet 80 and a spring pressed pawl 81 which is carried on a lever 82, which is pivotally mounted on the shaft of the roller 79, the outer end of the lever 82 120 being pivotally connected to a rod 83 which is adjustably connected to the end of the lever 71.

125 Thus it will be seen that as the rod 83 is raised, the pawl 82 will snap over the teeth of the ratchet 80, and then as the rod 83 drops 125 the pawl will engage the teeth of the ratchet thereby rotating the roller 79 a part of a revolution in a counterclockwise direction. Thus the gauze 75 is forced through by the feed rollers and it passes underneath a fixed block 84 which 130 has a sharp shearing rear edge, the opposite member of the shear being carried by the block 74. Thus as the block raises it cuts off the portion 85 of the gauze 75, and the portion so severed serves as a "super". This super is then 135 raised by the block 74, and when near the bottom of the book A a blast of air from a pipe 86, connected to a blower, (not shown) serves to lift the super 85 into contact with the glued back of the book where it adheres and is carried 140 forward by the book. As the rods 72 and 83 then fall a new portion of the gauze 75 is forced through to be cut to form the next super.

145 The book then passes on to the cover feeding and applying means G which is not shown herein in detail, but which is shown in the Bredenberg patent above referred to. The cover J is then applied as described therein, or in any other desired way, the book and cover then 150 passing around the rounded guides 87.

As the rollers 23 strike the cam 24, the rollers ride up on the cam forcing the plates 20 outwardly and releasing the bound and covered books which drop on the delivery conveyor H, 5 by which they are carried off.

Referring now to Fig. 2, the "gathered" but uncut and unbound books A' are carried to the chain 14 by means of a conveyor 88 which runs in timed relation to the chain 14 so that each 10 book A' is fed to one of the chain links 14 while it is held open by the cam 24. On running off the upper end of this conveyor the book A' is positioned by the horizontal table 89 carried by the main frame at which time the 15 roller passes off the end of the cam 24 thereby gripping the book to be bound.

This book is then trimmed by the band saw B which is driven by the pulley B' on the shaft 28 and runs over another pulley (not shown). 20 This trimmed book is then ready to be glued as previously described. Thus it will be seen a machine is provided for applying a suitable thin glue for holding the leaves of the book, and for satisfactorily applying thereto a heavy glue 25 which is well adapted to hold the cover of the book under conditions which will insure the two kinds of glue adhering to the book.

While we have shown and described but a single embodiment of our invention, it is to be understood that it is capable of many modifications. Changes, therefore, in the construction and arrangement may be made which do not depart from the spirit and scope of the invention as disclosed in the appended claims.

35 We claim:

1. In a mechanism for gluing the back edges of books and the like, means for applying glue to the edges of the books, means for chilling the glue thus applied, and means for applying glue 40 to the glued edges subsequent to chilling same.

2. In a mechanism for gluing the back edges

of books and the like, means for applying glue to the edges of the books, a housing through which the glued portions of the books pass, means for chilling the housing, and means for applying glue to the glued edges subsequent to chilling the same. 80

3. In a mechanism for gluing the back edges of books and the like, means for applying glue to the edges of the books, a housing through which the glued portions of the books pass, said housing having means for holding a refrigerant for chilling the glued portions, and means for applying glue to the glued edges subsequent to chilling the same. 85

4. In a mechanism for gluing the back edges of books and the like, means for applying glue to the edges of the books, means for scraping off excess glue, means for chilling the glued portions, and means for applying glue to the glued edges subsequent to chilling the same. 90

5. In a mechanism for gluing the back edges of books and the like, means for applying glue to the edges of the books, a U-shaped housing through which the glued portions of the books pass, a perforated passage communicating with 100 said housing, and a chamber for holding a refrigerant communicating with the passage.

6. In a mechanism for gluing the back edges of books and the like, means for applying relatively thin hot glue to the edges of the books, 105 means for simultaneously spreading the leaves at the point of application of the glue, means for applying the pressure to the sides of the book adjacent the glued portions to force the glued edges together, a housing through which the 110 glued portions of the books pass, means for chilling the housing, and means for applying a heavier glue over the chilled glue.
